(57) **CLAIM**

The ornamental design for a utility desk, as shown and described.

DESCRIPTION

FIG. 1 is an upper front perspective view of the first embodiment of a utility desk, showing our new design;

FIG. 2 is an upper perspective view of the rear of the utility desk of FIG. 1;

FIG. 3 is a front elevation view of the utility desk of FIG. 1;

FIG. 4 is a side elevation view of the utility desk of FIG. 1;

FIG. 5 is a rear elevation view of the utility desk of FIG. 1;

FIG. 6 is a side elevation view of the utility desk of FIG. 1;

FIG. 7 is a top plan view of the utility desk of FIG. 1;

FIG. 8 is a bottom plan view of the utility desk of FIG. 1;

FIG. 9 is an upper front perspective view of the second embodiment of a utility desk, showing our new design;

FIG. 10 is an upper perspective view of the rear of the utility desk of FIG. 9;

FIG. 11 is a front elevation view of the utility desk of FIG. 9;

FIG. 12 is a side elevation view of the utility desk of FIG. 9;

FIG. 13 is a rear elevation view of the utility desk of FIG. 9;

FIG. 14 is a top plan view of the utility desk of FIG. 9; and,

FIG. 15 is a bottom plan view of the utility desk of FIG. 9.

All broken line portion of the figure drawings is included to show portions of the article that form no part of the claimed design.

1 Claim, 14 Drawing Sheets
